(57) **CLAIM**

The ornamental design for a voice recording/reproducing device, as shown and described.

DESCRIPTION

FIG. 1 is a front, top and right side perspective view of the voice recording/reproducing device showing my new design. FIG. 2 is front elevational view thereof; FIG. 3 is a rear elevational view thereof; FIG. 4 is a top plan view thereof; FIG. 5 is a bottom plan view thereof; FIG. 6 is a right side view thereof; and, FIG. 7 is left side view thereof.

The broken lines shown in the drawings represent portions of the voice recording/reproducing device that form no part of the claimed design.
